PACKAGING CONTAINER

Joe Tiep, Darin Tiep, and Herbert Tiep, North Hollywood Calif., assignors to Carrousel Party Favors, Inc., North Hollywood, Calif.

Filed May 7, 1973, Ser. No. 357,724

Term of patent 3½ years

Int. Cl. D9—03

U.S. Cl. D9—191

FIG. 1 is a perspective view of a packaging container showing our new design;

FIG. 2 is an end elevational view;

FIG. 3 is a top plan view;

FIG. 4 is a bottom plan view;

FIG. 5 is a perspective view, partially broken away, of the inner platform; and

FIG. 6 is a perspective view of the platform portion of another embodiment of my new design wherein only the platform has been modified as shown.

We claim:

The ornamental design for a packaging container, substantially as shown and described.
